UNITED STATES PATENT OFFICE.

ERNEST H. CLARK, OF BIRMINGHAM, ALABAMA.

RECORD-BOOK.

1,353,315.

Specification of Letters Patent. Patented Sept. 21, 1920.

Application filed November 19, 1918. Serial No. 263,218.

To all whom it may concern:

Be it known that I, ERNEST H. CLARK, a citizen of the United States of America, residing at Birmingham, in the county of 5 Jefferson and State of Alabama, have invented certain new and useful Improvements in Record-Books, of which the following is a specification.

My invention relates to record books 10 which are particularly adapted for recording railroad car movements or other matters such as claims, files or documents which have index numbers and which progress from point to point or which require to be 15 traced and located.

My invention more particularly is intended as an improvement on the type of car record book patented to Augustus J. Camp on October 26th, 1909, No. 937,923, 20 wherein is shown 100 groups of original entry pages, each group having printed index numerals for entry spaces arranged in ten sub-groups characterized by having two like terminal digits and each sub-group 25 having an initial digit progressing by sub-groups in numerical order from 0 to 9, the space in advance of the printed numerals being provided to receive the initial digits of the car number, there being also opposite each number two horizontal columns of 30 spaces to receive the entries of the inbound and outbound car movements. In addition to the 100 groups of original entry sheets, the Camp record book has a supplement 35 comprising relatively smaller groups of entry spaces having a similar arrangement of groups and subgroups of indexing numerals. When any group of spaces on the main entry pages has been filled it was necessary 40 for further entries to turn to the supplement and find the group of spaces having corresponding index numerals and there to enter such additional car numbers as they occurred. The disadvantage of this is that 45 it necessitates the clerk searching at two remote and entirely disconnected places in the book in order to trace any given car number and as a result it has been found to cause the loss of considerable time and to be the 50 occasion of many errors. In practice it has been found to be necessary that each ten sub-groups of numerals having like terminal digits be arranged on not more than four successive pages as any other arrangement 55 makes too bulky a book or provides too small a number of entry spaces for each

group to give the book practical value. In the Camp patent each ten sub-groups of numerals are displayed on one pair of oppositely facing pages and as a result the 60 entry spaces under each group are necessarily limited, thereby enforcing an increased use of the supplement at the back of the book with the objectionable results above referred to. It is likewise necessary that a 65 sub-group of similar numerals be not divided between pages as in practice this has been found to occasion many errors through failure of the clerk to follow over from page to page in searching. My object is to avoid 70 these objections by a novel arrangement of each ten sub-groups of numerals on four main entry pages so as to provide each group of four pages with spaces for supplemental entries carried over from its respective ten sub-groups of entry spaces. By this 75 novel arrangement each ten sub-groups of entry spaces indexing numerals with two like terminal digits have associated with them a supplement, the spaces of which have the two index digits common to its respective sub-groups of main entry spaces. By causing the first three pages of each 80 group of pages to carry three sub-groups of main entry numerals, the fourth page needs 85 to carry only the final sub-group of main entry spaces, thus leaving two-thirds of it for the supplement spaces.

My invention will be more readily understood by reference to the accompanying 90 drawings which illustrate a typical embodiment of my invention as adapted for car record movements, and in which:

Figure 1 shows the book open to display the first two pages carrying the first six 95 sub-groups of entry spaces having indexing numerals terminating in the digits 00 and partially broken away to show a corresponding page of the last group of pages having the indexing numerals terminating 100 in the digits 99.

Fig. 2 is a similar view of Fig. 1, showing the second two pages of the first group of pages carrying the last four sub-groups of entry spaces having indexing numerals 105 terminating in the digits 00 together with their supplement, the book being broken away to show in part a corresponding page of the last group of pages having indexing numerals terminating in the digits 99. 110

Similar reference numerals refer to similar parts throughout the drawings.

As illustrated, I provide a book 1 provided with 100 groups of entry pages, each group comprising four pages (two oppositely facing pairs), respectively, numbered 5 2, 3, 4 and 5. As the pages comprising each group are similar, except as to the printed indexing numerals thereon, the arrangement of the first group of pages may be taken as typical of the other ninety-nine groups of 10 pages for the purpose of simplifying description. Page 2, which constitutes the first page of each group, is subdivided by a vertical divisional line 15 arranged near its center and the arrangement of columns and 15 entry spaces on each side of this line 5 being the same, with one exception hereafter noted, it will only be necessary to describe in detail this arrangement for one side of the page. At the left hand edge of the page 20 is arranged a vertical column 6 and adjoining this is a vertical column 7 headed by the word "Initial." Adjoining the column 7 is a vertical column 8 headed by the words "Car number" and subdivided into six 25 vertical sub-columns. Adjoining the column 8 is a vertical column 9 headed by the word "Movements" and divided into any desired number of vertical sub-columns. The several columns 6 to 9, respectively, 30 are subdivided by horizontal column lines 10 which extend entirely across the page and by horizontal sub-column lines 11 arranged to divide each horizontal column only across the "Movement" columns 9. 35 These horizontal sub-columns in the column 9 are arranged in alinement with the words "Inbound" and "Outbound" disposed opposite them in the column 6, but to avoid unnecessary printing these words "Inbound" and "Outbound" are displayed 40 only in the first horizontal column of each group of horizontal columns, which groups are divided and separated by the heavy horizontal lines 12. The other and inner half of 45 the page is provided with like columns 7, 8 and 9 and, except for the absence of the column 6, is a duplicate of the arrangement already described for the outer half of the page. It will be observed that said page is 50 divided by the vertical line 15 and the horizontal lines 12 into six groups of entry spaces which are similar, the spaces in column 6 not being, properly speaking, entry spaces. The two upper groups are distinguished 55 by having printed in the three terminal sub-columns of column 8 the indexing numerals 000, it being preferable to use ditto marks in place of the two final digits in all by the top columns, thus making the 60 initial or characteristic digit more prominent. The second two groups of spaces are distinguished by having the indexing numerals 1 00 printed in column 8 and the third two groups of spaces by having the indexing numerals 2 00 printed therein. 65

Page 3 is ruled and subdivided exactly as page 2 and its three main groups of spaces are distinguished by having printed therein the indexing numerals 3 00, 4 00 and 5 00, respectively. Page 4 is similar to pages 2 70 and 3 except that the three main groups of spaces are distinguished by having printed therein the indexing numerals 6 00, 7 00 and 8 00, respectively. Page 5 has its upper portion ruled to correspond with the ruling of 75 the two upper groups of spaces for the pages described and these spaces are distinguished by having the indexing numerals 9 00 printed therein. A horizontal column 13 extending across the page and having displayed therein the word "Supplement" divides the rest of the page from the upper groups of spaces. The ruling of the page under the supplement column is identical 80 with that already described and these spaces 85 are distinguished by having printed therein in the two terminal sub-columns of the columns 8 the numerals 00 or ditto marks therefor as these numerals characterize all 90 of the indexing numerals of the ten sub-groups of spaces on that group of pages. The second group of four pages will be distinguished from the first group only by having the indexing numerals of its sub-groups 95 of entry and supplement spaces terminating in the digits 01 instead of 00, and each succeeding group of pages successively throughout the book will be characterized by indexing numerals, the terminal digits of which progress serially in numerical order from 02 100 to 99. Any desired arrangement of tabs 14 can be employed, that preferable being the arrangement of a tab on the middle sheet of each group of four pages having displayed 105 on both sides thereof the two terminal digits 105 characteristic of the indexing numerals of its respective groups of entry spaces. By this means the tab may be grasped and the book readily opened to expose all ten sub-groups and their respective supplement 110 which have the terminal indexing digits corresponding to those on the tab page to the right or the left the spaces desired for search or entry are made accessible.

In operation, it is desired to make entry 115 of the movements of a given car, for instance B & O No. 41200, the book is opened at the initial index tab marked 00 and the entry is made in the sub-group of entry spaces carrying the terminal digits "200". 120 In entering the car its initial "B & O" is entered in column 7 and its initial digits "41" are entered in the appropriate sub-columns in column 8. Thereafter entries of the inbound movements of this car are 125 made in the upper horizontal sub-column in column 9 while its outbound movements are made in its respective lower horizontal sub-column in column 9. The number of vertical sub-columns in the column 9 may be 130

increased to receive the ordinary number of entries required. In practice about seven of these columns are used for car movements though only four are disclosed for illustrative purposes in the drawings. If the next entry were for a car numbered 2399 the tab marked "99" would be grasped and the book opened and the entry made in the sub-group of spaces characterized by the terminal digits 5 399. In this way entries accumulate until all sub-groups of entry spaces, which are similarly numbered, are filled. Thereupon the next entry is made in the supplement columns characterized by the two terminal digits similar to the car number, thus, 10 in the first instance, if all entry spaces headed "200" had been filled when it was desired to enter car number 41200 this entry would then have been made in the supplement on 15 page 5 by entering the first three digits of the car number, to-wit:—"412" in the appropriate sub-columns of column 8.

It will be observed that instead of dividing each page into three large sub-groups 20 of entry spaces, I provide for a large number of original entry spaces for each sub-group. This division of each page into three main groups of spaces is of peculiar 25 importance as it leaves only one sub-group 30 of spaces for the fourth page of each group of pages, thus releasing two-thirds of this latter or fourth page for supplemental entries. This arrangement also confines all 35 similarly numbered entry spaces to the same page, thus avoiding errors which is most liable to occur if any similarly numbered groups of spaces are spread over two pages. In combining each supplement with its corresponding group of main entry spaces, I 40 condense at one point in the book all entries having two corresponding terminal digits and I avoid two separate groups of main entry and supplement pages and also the necessity for two sets of indices and of cross 45 references from one to another which would otherwise be essential.

It will be understood that the particular 50 headings of the columns will be modified in accordance with the character of the subject matter to be entered, whether the same relate to car movements, claims, vouchers or other documents, and that the number of 55 columns or the subdivisions thereof may be increased or diminished in accordance with the nature of the entries, it being within the contemplation of my invention that the same shall embrace any equivalent arrangement of ten indexed sub-groups of entry spaces and their correlated supplement 60 entry spaces when distributed in the manner described over four succeeding pages.

Having thus described my invention, what I claim as new and desire to secure by Letters Patent, is:—

65 1. An improved record book comprising

100 groups of four entry pages, each page being subdivided by vertical and horizontal lines into entry spaces, each entry space of a group of pages being headed by an indexing numeral having two like terminal digits, 70 the entry spaces of the first three pages and part of the fourth page of each group of pages being divided into like sub-groups which are respectively distinguished by a different initial index digit, which initial 75 digit progresses by groups in numerical order from zero to nine, the two terminal digits characterizing each of the 100 groups of pages progressing by groups in numerical order from 00 to 99. 80

2. An improved record book comprising 100 groups of pages, there being four pages to each group, all the pages being subdivided by vertical and horizontal lines into entry spaces which are headed by indexing digits 85 which progress by groups of pages in numerical order from 00 to 99, the entry spaces of each group of four pages being subdivided into ten equal sub-groups of original entry spaces and one larger sub-group of 90 supplemental entry spaces, the ten sub-groups of original entry spaces being further distinguished from each other by the addition of an initial indexing digit to their aforesaid respective index digits, which initial 95 digits progress by sub-groups of original entry spaces in numerical order from 0 to 9.

3. An improved record book comprising 100 groups of pages, there being two pairs 100 of oppositely facing pages to each group, all the pages being subdivided by vertical and horizontal lines into entry spaces which are headed by indexing digits which progress by groups of pages in numerical order from 105 00 to 99, the entry spaces of each group of pages being subdivided into ten equal sub-groups of original entry spaces and one relatively larger sub-group of supplemental entry spaces, the ten sub-groups of original 110 entry space being further distinguished by the addition of an initial index digit to their respective index digits aforesaid, which initial digits progress by sub-groups of original entry spaces in numerical order from 0 to 9, three sub-groups of spaces being arranged on each page of a group of pages except the last page, two thirds of which is devoted to said sub-group of supplemental entry spaces. 115

4. An improved record book comprising 100 groups of pages, there being four pages to each group, each page of a group being subdivided by vertical and horizontal lines into sub-groups of entry spaces, each group 125 of pages being ruled into ten equal sub-groups of original entry spaces and one group of supplemental entry spaces twice the size of an original entry sub-group, the ten sub-groups of original entry spaces on 130

- each group of pages having a common indexing numeral composed of two terminal digits and being distinguished by the pre-fixing of an initial indexing digit which 5 progresses by sub-groups in numerical order from 0 to 9, the two terminal indexing digits for the groups of pages progressing by groups of pages in numerical order from 00 to 99.
- 10 5. An improved record book comprising 100 groups of pages, there being four pages to each group, each page of a group being subdivided by vertical and horizontal lines into sub-groups of entry spaces, there being 15 ten sub-groups of original entry spaces and one sub-group of supplemental entry spaces distributed over each four original entry pages, each sub-group of spaces having a distinguishing index numeral composed of
- two terminal digits which are alike on each 20 group of pages, the first ten sub-groups of spaces on each group of pages being distinguished by an initial indexing digit which progresses by sub-groups in numerical order from 0 to 9, the terminal indexing digits for the groups of pages progressing by groups of pages in numerical order from 00 to 99, each group of four pages comprising two pairs of oppositely 25 facing pages, and an index tab connected to the leaf carrying the middle pages of each group of pages and displaying the characteristic index digits of its respective group of pages.

In testimony whereof I affix my signature.
ERNEST H. CLARK.
